[57] **CLAIM**

The ornamental design for a shotgun shell loading press, substantially as shown and described.

DESCRIPTION

FIG. 1 is a front elevational view of a shotgun shell loading press which embodies my new design;

FIG. 2 is a rear elevational view thereof;

FIG. 3 is a side elevational view thereof, taken from the left side of FIG. 1;

FIG. 4 is a side elevational view thereof, taken from the right side of FIG. 1; and

FIG. 5 is a top plan view thereof.
